UNITED STATES PATENT OFFICE.

EDWARD F. McCOOL, OF VICTOR, COLORADO.

ORE-GRINDER.

1,138,966.

Specification of Letters Patent. Patented May 11, 1915.

Application filed July 3, 1911. Serial No. 636,778.

To all whom it may concern:

Be it known that I, EDWARD F. McCOOL, a citizen of the United States, residing at Victor, in the county of Teller and State of Colorado, have invented a new and useful 5 Ore-Grinder, of which the following is a specification.

This invention relates to an improvement in ore grinders.

10 The primary object of the invention is the provision of a machine of the type in which a plurality of disks are employed, one of said disks being stationary, the other being capable of a combined rotary and rocking motion.

15 A further object of the invention is to provide means for conveniently removing and replacing the disks and to provide means for adjusting the movable disk in order to vary the quality of the ground product.

20 In the drawings, Figure 1 is a longitudinal section. Fig. 2 is a top plan view. Fig. 3 is a section on the line 3—3 of Fig. 1, and Fig. 4 is a section on the line 4—4 of Fig. 1. 25 Fig. 5 is a front elevation of the disk 37. Fig. 6 is a front elevation of the clutch member 36. Fig. 7 is a front elevation of the stationary disk. Fig. 8 is a perspective view of the disk 37. Fig. 9 is a perspective view of the disk 36. Fig. 10 is a perspective view of the disk 31. Fig. 11 is a horizontal cross section through one of the fastenings for securing the stationary grinding disk to 30 the frame. Fig. 12 is a perspective view of a clip used in said fastener. Fig. 13 is a detail sectional view taken upon the line 13—13, Fig. 1.

35 In the drawings 10 designates a casing which is arranged to support a sleeve 11, the casing being so formed as to house the end portions of said sleeve. Arranged intermediate the ends of said housings is a pulley by means of which the sleeve is driven. As 40 before stated the end portions of the sleeve 11 extend within the portions 14 and 15 of the casing being supported by bearings 16 and 17, the sleeve being spaced from said bearings by a babbitt insert 19 and arranged 45 immediately below each of the bearings is an oil reservoir 20, an oil distributing ring 21 embracing the sleeve and extending within each said reservoir thus lubricating the sleeve. The bearing 16 is provided with an auxiliary oil chamber 20' oil passing from the chamber 20' through the passage 22 and

being fed from said chamber to the loose pulley 13 which is arranged within the sleeve 11. The casing 14 is designed to house a set of gears which transmit the rotary movement of the sleeve to a shaft which is eccentrically arranged within the same. This transmission consists of a gear 24 mounted on the sleeve 25 which extends within and is secured to the sleeve 11. The gear 24 is in mesh with the gear 25' mounted on the stub shaft 26 which supports the second gear 27 and which is supported by a plurality of links 28, the gear 27 being in mesh with gear 29 mounted on the shaft 23. 50 It will be noted by this construction that the sleeve and shaft, travel at different speeds.

55 As clearly illustrated in Fig. 13, the portion 55 of the sleeve 25 upon which the gear 24 is mounted is concentric with the shaft 23. Accordingly, all of the gears remain in fixed relation with each other but they have a common up and down motion due to the eccentricity of the shaft and the portion 55 of the sleeve with relation to the sleeve 25. 60

65 The portion 15 of the casing is arranged to contain the grinding mechanism which as before stated consists of a stationary and a rotary disk. The portion 15 supports a hinged housing 15' which is formed with a hopper 30 which discharges at a point slightly above the center of the casing. To the hinged portion of the casing 15 is secured the stationary grinding disk 31, gaskets 31' being arranged between said disk and casing to exclude dust, this disk being formed with a plurality of projections 32 which pass through openings 33 in the casing, which projections 32 terminate in T-shaped extensions, tapered U-shaped members 34 embracing the T-shaped end portions and securely clamping the disk. It will be noted by this construction that the disk may be readily moved and replaced when the same becomes worn. Arranged 70 adjacent the end of the shaft 23 and rotat- 75 ing therewith is clutch disk 35 which is formed with a clutch face 36 which receives a plurality of projections carried by grinding disk 37. The clutch face of the disk 35 is provided with the tapered re- 80 cesses 38 which receive the tapered por- 85 tions 39 of the projections 40 carried by the disk 37, a plurality of springs 41 prevent- 90 ing the accidental displacement of said pro- 95 jections. In assembling the disks 35 and the grinding disk 37 the projections car- 100 105 110

ried by the disk 37 are placed within the recess 43 formed in the disk 35 and rotated until the same lie beneath the springs 41, this rotation in assembling the disks being 5 in the direction of their drive. To remove the grinding disk however, the same is rotated in a direction the reverse of its drive its projections thus coming from beneath the springs 41. Particular attention is 10 called to this manner of securing the grinding disk 37 as the same may be readily removed and replaced when it becomes worn access being readily had to said disks by swinging the hinged portion of the casing 15 outwardly. The disk 37 is provided centrally with a socket 43' which receives the rounded end of the shaft 11, said shaft at its end portion acting as a pivot for said disk thus providing for a rocking as well 20 as a rotary movement. The disk 37 is of a diameter in excess of the disk 35 and is provided with the portion 37' which overhangs said disk 35, the difference in the 25 diameters of the two disks however permitting the aforesaid rocking movement. Embracing the reduced portion of the disk 35 and interposed between said disks and the bearing is a dust guard 45 which is mounted on the insert which is interposed 30 between the sleeve and the shaft 11, this dust guard 45 effectually preventing dust from entering said bearings. When power is applied to the sleeve 11 it is transmitted to the shaft 23 through the medium of the 35 transmission gear arranged in the portion 14 of the casing, the gearing between said shaft and sleeve being such that the said shaft and sleeve rotate at different speeds, and the fact that the shaft is mounted eccentrically 40 within the sleeve assures a rocking motion of the disk 37 as well as a rotary motion. This peculiar driving mechanism is to prevent the grinding disks from becoming grooved as by such construction the disks 45 will seldom grind in the same position.

In order to adjust the rotary disks relative to the stationary disks the feed screw 46 is provided and arranged to extend within the casing 14 its end portions contacting 50 with the longitudinally movable block 47 which as the screw 46 is advanced contacts with the end portion of the shaft 23 to advance the same to the desired degree, attention being called to the fact that the projection 47 will take up the wear incident to its contact with the end portion of the shaft 23, said block 47 being readily replaced as the same becomes worn.

The many advantages of a machine of 60 this kind will be clearly apparent as it will be noted that the grinding disks may be readily removed and replaced, the action of the movable disk being such that said plates

will not become grooved. Attention is also called to the fact that the movable plates 65 may be readily and conveniently adjusted in order to vary the degree of fineness to which the product is ground.

What is claimed is:—

1. In an ore grinder, a sleeve, means for 70 driving said sleeve, a shaft eccentrically supported within said sleeve, means for transmitting the motion of said sleeve to said shaft, a grinding disk pivotally supported by the end portion of said shaft and 75 means carried by said shaft to rotate said disk.

2. In an ore grinder, a casing, a sleeve supported by the casing, a shaft eccentrically mounted within said sleeve, means for 80 rotating said sleeve and shaft at different speeds, a grinding disk pivotally supported by said shaft, means carried by said shaft for rotating said disk and a fixed grinding disk supported upon the casing adjacent 85 said rotating disk.

3. In an ore grinder, a sleeve, a shaft eccentrically supported within said sleeve, a grinding disk pivotally supported by said shaft, a disk mounted on said shaft adjacent 90 said first mentioned disk, means for locking said disks together, a bearing supporting said shaft eccentrically of said sleeve and adjacent one of its ends, and an annular dust guard mounted on said bearing. 95

4. In an ore grinder, a shaft, a grinding disk in rocking engagement with one end of said shaft, a clutch disk supported upon said shaft adjacent said grinding disk, the rear of said grinding disk having arms extending laterally from a point opposite its center, said clutch disk having a portion of its forward face hollowed out, projections extending inwardly from the rim into the hollowed out portion, and one or more bars of 100 spring material secured at the ends of said rim and passing over a part of said hollowed out portion, said arms of the grinding disk being adapted to bear against the projections and under the spring members of the 110 clutch disk.

5. In an ore grinder, a sleeve, a shaft supported eccentrically within said sleeve, means for driving said shaft, a feed screw, a lug arranged between said feed screw and 115 the end portion of said shaft, the screw when advanced imparting longitudinal movement to said shaft independent of said sleeve.

In testimony that I claim the foregoing as my own, I have hereto affixed my signature in the presence of two witnesses.

EDWARD F. McCOOL.
